United States Patent Office

Des. 198,626
Patented July 14, 1964

198,626

GLASS BLOCK

Edward P. Lockart and William E. McWhorter, Toledo,
Ohio, assignors to Owens-Illinois Glass Company,
Toledo, Ohio, a corporation of Ohio

Filed July 2, 1963, Ser. No. 75,617

Term of patent 14 years

(Cl. D18—2)

FIG. 1

FIG. 1 is a front perspective view of a glass block showing our new design in detail;

FIG. 2 is a cross-sectional view taken along the line 2-2 of FIG. 1, and

FIG. 3 is a cross-sectional view taken along the line 3-3.

The other side, rear and bottom portions of the subject glass block are substantially the same as the respective side, front and top portions shown.

We claim:

The ornamental design for a glass block, as shown and described.
